UNITED STATES PATENT OFFICE

111,651

DESIGN FOR A SCAFFOLD UNIT

George W. Frost, Evansville, Ind., assignor to The Steel Scaffolding Company, Inc., Evansville, Ind., a corporation of Indiana

Application July 11, 1938, Serial No. 78,396

Term of patent 14 years

To all whom it may concern:

Be it known that I, George W. Frost, a citizen of the United States, residing at Evansville, in the county of Vanderburgh and State of Indiana, have invented a new, original, and ornamental Design for a Scaffold Unit, of which the following is a specification, reference being had to the accompanying drawing, forming part thereof.

The figure is a perspective view of a scaffold unit embodying my new design.

I claim:

The ornamental design for a scaffold unit,
as shown.

GEORGE W. FROST.
